UNITED STATES PATENT OFFICE.

JOSEPH M. YATES, OF CHARLOTTE, MICHIGAN, ASSIGNOR TO HANCOCK MANUFACTURING COMPANY, OF CHARLOTTE, MICHIGAN, A CORPORATION OF MICHIGAN.

DESIGN FOR A HANDLE FOR MOTOR-VEHICLE DOORS.

Application filed December 16, 1922. Serial No. 4,613. Term of patent 3½ years.

To all whom it may concern:

Be it known that I, JOSEPH M. YATES, a citizen of the United States, residing at Charlotte, in the county of Eaton and State of Michigan, have invented a new, original, and ornamental Design for Handles for Motor-Vehicle Doors, of which the following is a specification, reference being had to the accompanying drawings, forming part thereof.

Figure 1 is a front or plan view of the handle. Fig. 2 is a side elevation of a

handle embodying my new design. Fig. 3 is an end view of the same.

The dominating feature of the design is the novel effect obtained by the use of a longitudinal stripe of a color such as to produce a contrasting appearance upon the polished surface of the handle.

I claim:

The ornamental design for a handle for motor vehicle doors substantially as shown.

JOSEPH M. YATES.
